John Donovan

UNITED STATES PATENT OFFICE.

DAVID LINDSAY, OF LOUISVILLE, KENTUCKY.

LOCOMOTIVE-WHISTLE AMPLIFIER.

Application filed April 10, 1926. Serial No. 101,167.

This invention relates to attachments for the whistles of locomotives and has for its object the provision of a novel sound directing hood structure whereby the sound of 5 the locomotive may be projected forwardly in advance of the train and also rearwardly so as to give not only adequate signals to trainmen and other interested parties along the road, but also to warn motorists and 10 others at crossings whereby to prevent accidents.

It is well known that the ordinary type of locomotive whistle sends out the sound in all directions, the sound at the sides being 15 objectionable whereas the sound at the front and rear is at present totally inadequate inasmuch as it does not carry far enough or loud enough to be heard especially by motorists in closed cars.

20 It is with the above facts in view that I have designed the present invention which has for a more specific object the provision of a casing adapted to be attached in encircling relation to an already existing locomotive whistle and provided with megaphone portions which will extend forwardly and rearwardly for concentrating the sound into the proper directions.

An additional object is the provision of an 30 attachment of this character which will be simple and inexpensive in manufacture, easy to apply, positive in action, efficient and durable in service, and a general improvement in the art.

35 With the above and other objects and advantages in view, the invention consists in the details of construction and the arrangement of parts to be hereinafter more fully described and claimed, and illustrated in 40 the accompanying drawings, in which:—

Figure 1 is a plan view of the attachment applied to a locomotive whistle.

Figure 2 is a vertical section taken on the line 2—2 of Figure 1, and

45 Figure 3 is a similar view showing a slight modification in the structure.

Referring more particularly to the drawings, the letter A designates an ordinary locomotive whistle which, as is well known, 50 is generally supported upon the steam pipe B which supplies pressure thereto for the purpose of operating it. The letter C designates the usual elbow which is provided.

In carrying out the invention, I provide 55 a casing or hood structure 10 which may be of any suitable size, shape and material

but which must be large enough to surround the whistle A in spaced relation thereto. This casing 10 may be mounted in any desired manner as for instance in Figures 1 60 and 2 it is shown as having secured to its inner periphery at its lower end a plurality of angular arm members 11 which are riveted or otherwise suitably secured to a collar 12 embracingly engaged upon the pipe 65 C and held thereon by a set screw 13. Instead of being constructed in this manner, the bottom of the casing member may be closed as indicated at 14 in Figure 3, and formed with an integral collar 15 engaged 70 upon the pipe and secured thereto by set screws 16. It is immaterial which detail construction is followed or adopted. In either event, the top of the hood or casing is open so as to permit the steam from the 75 whistle to escape.

Formed or secured upon the opposite sides of the casing 10 at intermediate points in the length thereof are megaphones or funnel members 17 of suitable length which of 80 course communicate with the interior of the casing 10 through openings 18.

In the operation, it will of course be apparent that the whistle acts in the usual manner but the sound therefrom will be 85 directed forwardly and rearwardly of the train through the megaphones or funnel members 17, the sound being thus intensified and concentrated in the desirable directions and prevented from passing out to the sides 90 where the use is undesired. Clearly, trainmen or the operators of other trains in the rear will hear the signals and the same is true in the case of trains in advance. However, the principal feature of advantage is 95 that at railroad crossings the occupants of automobiles, especially closed cars, will be enabled to hear the warning signal so that they will not attempt to cross the tracks in the path of a train. It is really believed 100 that the construction, operation and advantages will be readily apparent to one skilled in the art without further explanation.

While I have shown and described the preferred embodiment of the invention, it 105 should be understood that I reserve the right to make such changes in the form, construction and arrangement of parts as will not depart from the spirit of the invention or the scope of the subjoined claim.

Having thus described the invention, I 110 claim:—

A sound amplifying attachment for a locomotive whistle, the whistle including an upstanding pipe carrying the whistle and having an operating lever pivotally mounted upon the pipe beneath the whistle, the attachment comprising an open topped cylindrical casing disposable about the whistle in spaced relation thereto, said casing hav-

ing a slot therein for the accommodation of said lever, a cuff vertically adjustably 10 clamped upon the whistle supporting pipe and connected with the bottom of the casing, and oppositely arranged megaphone members carried by the casing and communicating with the interior thereof.

DAVID LINDSAY.
